UNITED STATES PATENT OFFICE

JOSEPH ANZALONE, OF NEW YORK, N. Y., ASSIGNOR TO ALCA CLOTHES DRYER MANUFACTURING COMPANY, INC., OF NEW YORK, N. Y.

CLOTHES DRIER

Application filed August 23, 1930. Serial No. 477,240.

This invention relates to clothes driers wherein a carrier for a series of clothes hangers is adapted to be mounted and supported in a window opening of a building to be adjusted to extend in a direction longitudinally of and to one side of the window opening and to position centrally of and extend outwardly from the window opening, and the hangers in said latter position of the carrier adapted to be adjusted on the carrier to position adjacent the window opening and outward in spaced relation, and it is the object of the invention to provide an improved construction and arrangement of drier of this character which is simple in structure and efficient in use.

In the drawings accompanying and forming a part of this application Figure 1 is a perspective view of my improved drier mounted in a window opening of a building and showing the hangers adjusted outward on the carrier therefor.

Figure 2 is a perspective view similar to Figure 1 but showing the drier adjusted to an operative position to extend longitudinally and to one side of the window opening.

Figure 3 is a cross sectional view to show the arrangement of adjustably mounting the clothes hangers on the carrier.

Figure 4 is a perspective view of one end of a clothes hanger.

Figure 5 is a perspective view of the means to mount and support the hangers from the carrier therefor.

Figure 6 is a side elevation, partly in section, and Figure 7 is a plan view of means to adjustably mount the hanger carrier upon a support in the window opening.

Figure 8 is a side elevation, partly in section, to show the pivotal connection of a sectional supporting arm for the hanger carrier.

Figure 9 is a side elevation of a support for the hanger-carrier mounted in the window opening; and

Figure 10 is a perspective view of the intermediate portion of a hanger to show the means for suspending the hangers from the support shown in Figure 5.

50 The embodiment of the invention illus-

trated comprises a carrier 11 in the form of a channel rail, pivotally connected at 12 adjacent to one end, to constitute the inner end, with one end of a supporting arm 13, the opposite end of the supporting arm being flattened and formed to hook shape whereby it is engaged and mounted upon a bar 14 supported at the ends by the opposite side walls of a window opening, the hooked end of the arm being releasably retained on the bar 14 by a pivoted catch 15. To retain the carrier 11 in position to extend substantially in parallel relation to the arm 13 the carrier is provided with a perforated ear 16 adapted to be extended through a perforation 17 in the arm 13 and retained in said position by a latch 18 pivoted upon the arm engaging the perforation in the ear, as shown in Figures 6 and 7. The outer end of the carrier is supported by an arm comprising a pair of pivotally connected sections 19, 20 to have adjustment toward each other in one direction, as shown in Figure 2, and to extended position, as shown in Figure 1, and the adjustment to extended position being limited by an abutment 21 carried by one arm section engaging with the other arm section, as shown in Figure 8. The section 19 has a flattened hook member 22 secured to the free end whereby it is mounted on a bar 23 supported at the ends by the opposite walls of the window opening similar to the bar 14. The free end of section 20 has a pivotal connection 24 with the carrier at a point within the outer end.

The supporting bars 14, 23 are of similar construction, (Figure 9,) each bar comprising a tubular member having a foot 25 secured at one end thereof, and a threaded stem carrying a foot, as at 25', is engaged in the opposite end of the tubular member, with a nut 26 threaded onto the stem abutting against the end of the tubular member. To mount the bars in the window opening the nut 26 is adjusted on the threaded stem until the feet 25, 25' engage the opposite walls of the window opening when the tubular member and stem are moved outward from each other and the feet forcibly impinged against the opening walls by screwing the nut out.

ward on the stem, as by a wrench. By arranging the hooked end of arm 13 and of arm section 19 the carrier is held against lateral movement relative to the supporting bars 5 14, 23.

A series of clothes hangers are supported from the carrier, in the present instance shown as three in number, each hanger comprising a rod 26' having cross heads 27 fixed 10 to the opposite ends with the ends perforated for the passage and securing of lines 28 thereto. The hangers are supported from the carrier rail 11 to have movement inward toward and outward from the window opening. 15 For this purpose a carriage for each hanger is mounted in the channel of the carrier 11, said carriages comprising a pair of rollers 29 rotatably mounted on the reduced ends of axles 30, the hangers being releasably suspended from said carriages by a T-member 31 fixed intermediate the ends of the hanger rods 26' and adapted to be engaged upon bifurcated hooked members 32 fixed to the carriage axles 30. The hanger carriages are 20 adjusted relative to the carrier 11 by a cable 33 extended about a pulley 34 at the outer end of the carrier, to one end portion of which cable the hanger carrying carriages are connected in spaced relation by connecting the cable with the hanger carrying hooked members 32, as at 35, by extending the cable through perforations in said hooked members, as by knotting the cable at opposite sides thereof, the cable being secured in position 25 with the hanger carriages adjusted outward on the carrier, as shown in Figure 1, by securing the opposite ends of the cable together and to the supporting bar 14. The opposite end portion of the cable is guided by the connection members 12, 24 of the arms 13, 20 with the carrier.

The carrier 11 when not in use is adapted to be adjusted to extend longitudinally and to one side of the window opening, as shown 45 in Figure 2. For this purpose the hook 18 is released from the perforation of ear 16 permitting the end of the carrier 11 to drop away from the arm 13 when a pull is exerted on a cable 36 connected at 37 with the carrier and extended through an eyelet or a pulley carried by the hook member 22 of the arm section 19, as at 38, and the carrier 11 secured in such position by fastening the cable to the supporting bar 14. The carrier supporting arms 13 and 19 may be adjusted to the 50 side of the window opening either before or after the carrier 11 has been adjusted to the position shown in Figure 2. To lower the carrier the cable 36 is released from the bar 14 and the carrier gradually lowered until it is supported by the arms 19, 20 when the inner end is connected with the arm 13 by the hook 18 engaging the perforated ear 16.

Having thus described my invention I 60 claim:

1. In a clothes drier, a channel rail, means adapted to be mounted in a window opening to support the channel rail to extend outward from said opening with the channel opening at the bottom, line carrying hangers 70 adjustably mounted in the channel rail, and means to connect and adjust the hangers on the channel rail outward from and inward toward the window opening.

2. In a clothes drier, a pair of supporting bars adapted to be mounted at the ends upon the opposite walls of a window opening in superposed parallel and spaced relation, a channel rail, an arm pivotally connected at one end with the channel rail and mounted at 75 the opposite end on the lower supporting bar, and an arm embodying hingedly connected sections, one section being pivotally connected with the channel rail and another section pivotally mounted on the upper supporting 80 bar.

3. In a clothes drier, a pair of supporting bars adapted to be mounted in a window opening to extend transversely thereof in superposed and spaced relation, a carrier rail, an 85 arm pivotally mounted at one end on the lower supporting bar and pivotally connected with the carrier rail within one end thereof, means to releasably connect the carrier rail and arm to extend in parallel relation, a second arm comprising a pair of hingedly connected sections, one section pivotally mounted on the upper supporting bar and the other section pivotally connected with the carrier rail adjacent the end opposite to that at 90 which the first arm is connected and said carrier rail being adapted to be adjusted and supported in position to extend outward from the window opening and to position to extend longitudinally and at one side of the window 95 opening, clothes hangers, means to mount the hangers on the carrier rail to have adjustment longitudinally thereof, and means to adjust said carrier rail.

4. A clothes drier as claimed in claim 3, 100 wherein the carrier rail is of channel form supported by the arms with the channel opening to the bottom, and the means to mount the hangers thereon comprising carriages mounted in the channel of the rail from which 105 the hangers are suspended.

5. A clothes drier as claimed in claim 3, 110 wherein the portions of the rail carrying arms engaged upon the supporting bars are flattened and of greater width than thickness to prevent lateral canting movement of the arms relative to the supporting bars.

6. A clothes drier as claimed in claim 3, 115 wherein the means to mount the hangers on the carrier rail comprises carriages rotatably supported by the carrier rail, and each carrier provided with a bifurcated hook member, and T-members connected with the hangers adapted for removable connection with the bifurcated carriage hooks.

7. A clothes drier as claimed in claim 3, wherein the clothes hangers comprise a rod supported intermediate the ends from the mounting means therefor on the carrier rail and having cross heads fixed to the opposite ends, and lines extended between and secured to the ends of the opposite heads.

8. A clothes drier as claimed in claim 3, wherein the means to connect the carrier rail and one supporting arm to extend in parallel relation to said arm, comprises a perforated ear projected laterally from the carrier rail and extended through a perforation in the arm, and a latch pivotally carried by the arm for engagement with the ear perforation.

9. A clothes drier as claimed in claim 3, wherein the carrier rail supporting rods each comprises a tubular member carrying a foot at one end, a threaded stem carrying a foot engaged in the opposite end of the tubular member, and a nut on the threaded stem in abutting relation to the end of the tubular member.

10. A clothes drier as claimed in claim 3, wherein the means to mount the hangers on the carrier rail comprises carriages, and means to which the carriages are connected in spaced relation to adjust the hanger carriers on the carrier rail outward from and toward the window opening.

Signed at the city, county and State of New York, this 19th day of August, 1930.
JOSEPH ANZALONE.
